UNITED STATES PATENT OFFICE.

DAVID DILON LONG, OF RUSSELLVILLE, ARKANSAS.

DESIGN FOR A STOVE-GRADE.

SPECIFICATION forming part of Design No. 30,597, dated April 18, 1899.

Application filed January 19, 1899. Serial No. 702,755. Term of patent 7 years.

To all whom it may concern:

Be it known that I, DAVID DILON LONG, a citizen of the United States, residing at Russellville, in the county of Pope and State of 5 Arkansas, have invented and produced a new and original Design for a Stove-Grate; and I do hereby declare the following to be a full, clear, and exact description of the same, reference being had to the accompanying drawings, in which—

Figure 1 shows a plan view, and Fig. 2 a cross-section thereof.

The leading or characteristic feature of my design comprises the unitary article, as shown 15 in the accompanying illustration, wherein lines radiating from a smooth center are disclosed, and wherein the cylindrical periphery of the article is provided with recesses, as shown.

A represents the grooves in the solid plate. 20 B represents the square recesses placed at regular intervals therein.

C represents a handle or projection provided with a perforation at the end.

D represents the center of the grate, provided 25 with an opening.

E indicates the slightly-scalloped outline of the article.

Having thus described my design, what I claim as new, and desire to secure by Letters 30 Patent, is—

The design for a stove-grate, substantially as herein shown and described.

In testimony whereof I affix my signature.

DAVID DILON LONG.
